UNITED STATES PATENT OFFICE

CHARLES DAVID BONNALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA

CAR ROOF

Application filed December 31, 1930. Serial No. 505,760.

This invention relates to car roofs of the type wherein the metal roof sheets are riveted together and to the tops of interior carlines along their adjacent margins. It has for its principal objects to produce a strong and light weight roof of simple and economical construction that is easy of application and that will prevent any water that may leak through the roof joints or around the rivets that secure the sheets to the carlines from reaching the interior of the car. Other objects are to increase the strength and rigidity of the carlines and to secure effective ventilation of the car. The invention consists in the car roof and in the construction, combinations and arrangements of parts herein-after described and claimed.

In the accompanying drawings, which form part of this specification and wherein like symbols refer to like parts wherever they occur.

Fig. 1 is a plan view of a portion of a car roof embodying my invention,

Fig. 2 is an enlarged vertical transverse cross-section through one-half of the car roof on the line 2—2 in Fig. 1,

Fig. 3 is a similar but further enlarged cross-section through the eaves portion of the roof,

Fig. 4 is a vertical transverse cross-section through the eaves portion of the roof, the section being taken through one of the carlines on the line 4—4 in Fig. 1,

Fig. 5 is a horizontal cross-section through one of the side plates and the downturned end of a carline and the adjacent roof sheets on the line 5—5 in Fig. 4,

Fig. 6 is a plan view of a portion of one of the side plates and the portion of the carline secured thereto,

Fig. 7 is a vertical transverse section through the ridge portion of the car, the section being taken through one of the carlines on the line 7—7 in Fig. 1,

Fig. 8 is a vertical cross-section through one of the carlines at the ridge on the line 8—8 in Fig. 2,

Fig. 9 is a similar cross-section through one of the carlines, the section being taken inter-

mediate the ridge and eaves on the line 9—9 in Fig. 2,

Fig. 10 is a perspective view of one of the side sections of the sectional closure plate of a carline,

Fig. 11 is a perspective view of the ridge section of said sectional carline closure plate;

Fig. 12 is a perspective view of one of the end sections of said sectional carline closure plate.

The present roof comprises side plates A of Z-section with their inner flanges A' upstanding. The side plates are connected by hollow box girder interior carlines B that slope downwardly on opposite sides of the ridge to conform to the slope of the roof and have depending end portions B' that overhang the upstanding inner flanges A' of said side plates and are left open at their lower ends to provide for drainage and ventilation. The carlines B are of substantially uniform depth from the ridge to points adjacent to the eaves where their depth is reduced where they are curved downwardly to form their depending ends B'. Metal roof sheets C extend from side plate to side plate and are provided at their eaves ends with depending flanges C' that overhang and are rigidly secured to the upstanding inner flanges A' of the side plates A and the depending end portions B' of the carlines B by rows of horizontal rivets 2. The roof sheets have their side marginal portions overlapped and rigidly secured together and to the tops of the carlines B by rows of rivets 2.

Running boards 3 extend longitudinally of the car at the ridge and are supported on the lateral top flanges of Z-shaped running board saddles 4 whose lateral base flanges rest on the roof sheets above the carlines and are rigidly secured to the carlines by the rows of rivets 2 that secure the lapped margins of said roof sheets to the tops of said carlines.

The carlines B are made of two members each. The upper member 5 is in the form of an inverted channel with outstanding base flanges 6 at the lower edges of its side walls. The lower carline member is in the form of a sectional plate 7 of channel-shaped cross-sec-

tion that extends the full length of the car-line and is rigidly secured to the base flanges 6 of the upper carline member 5 and thus serves as a closure plate for the downwardly opening channel therein. The lower carline member 7 is wider than the upper or main carline member 5 so that its upstanding side marginal flanges 8 are located beyond and extend above the base flanges 6 of said upper carline member. By this arrangement, any water that gets under the lapped margins of the roof sheets or through the holes for the rivets 2 onto the trough-shaped lower carline member or closure plate 8 will drain lengthwise of said plate and will be discharged through the depending ends of the carline B outside of the car. In order to ventilate the car, the lower carline member 7 is provided with a series of holes 9 that are spaced apart lengthwise of said member and serve to permit air that enters the open ends of the carlines to reach the interior of the car. As shown in the drawings, the holes 9 are offset with relation to the rivets located thereabove and have their edges flanged up, as at 10, so as to prevent water that leaks through the holes for the rivets from entering the car through said holes.

To facilitate assembly, the lower or bottom member 7 of each carline B is made in five sections of channel-shaped cross-section; namely, a ridge section 7a, relatively long duplicate side sections 7b and duplicate end or eaves sections 7c. The ridge section 7a of the lower carline member 7 slopes downwardly from its middle toward its ends to conform to the slope of the underside of the upper carline member 5 and is held in place beneath said upper member by extending the ridge end portions of the two side sections 7b beneath the adjacent ends of said ridge section. The end sections 7c are of angle-shape and have one leg that is riveted to the base flanges 6 of the upper carline member 5 and extends beneath the adjacent eaves end of the adjacent side section 7b. The other legs of the end sections 7c extend downwardly between the upstanding inner flange A' of the side plates A and the depending end portions of the upper or main carline member 5 and thus form the inner walls of the depending end portions B' of the carline B. In assembling the roof, the upper or main carline member 5 with the angular end lower carline sections 7c thereon are attached to the side plates A, the lapped side margins of the roof sheets are then secured to the tops of said upper carline members by the rivets 2, and the side and ridge sections 7a and 7b, respectively, are then secured to the base flanges 6 of said upper carline members and cooperate with the end sections 7c to form the bottom members or closure plates 7 of the carlines B which function as drain troughs or channels for carrying away any water that may leak between the

overlapped side margins of the roof sheets or through the holes therein for the securing rivets 2 therefor. The holes 9 in the bottom members 7 of the carlines serve to establish communication between the interior of the car and the interior of the hollow carlines, thereby permitting said carlines to function as passageways or flues for ventilating the car.

What I claim is:

1. A car roof comprising side plates, hollow carlines connecting said side plates, and roof sheets supported on and riveted to said carlines, each of said carlines comprising a hollow upper member and a sectional lower member secured to said upper member throughout the length thereof and extending over said side plates.

2. A car roof comprising side plates, carlines of hollow box section connecting said side plates, and roof sheets supported on and riveted to said carlines, each of said carlines comprising an upper member of inverted channel section and a lower plate-like member secured to the bottom of said upper carline member throughout the length thereof and extending over said side plates, said lower member consisting of a plurality of outwardly and downwardly inclined sections arranged with the outer ends of the inner sections overlapping the inner ends of the outer sections.

3. A car roof comprising side plates, carlines of hollow box section connecting said side plates, and roof sheets supported on and riveted to said carlines, each of said carlines comprising an upper member of inverted channel section and a lower plate-like member secured to the bottom of said upper carline member throughout the length thereof, said lower member consisting of a plurality of outwardly and downwardly inclined sections arranged end to end in overlapped relation, the end sections of said lower carline member having end portions depending beyond the side plates.

4. A car roof comprising side plates, carlines connecting said side plates, and roof sheets supported on and riveted to the tops of said carlines, each of said carlines comprising a main member of inverted channel-shaped section and a sectional lower plate-like member secured to said carline throughout the length thereof and extending beyond the side plates, said sectional lower member being wider than said main member and having its side margins flanged upwardly.

5. A car roof comprising side plates, carlines connecting said plates, and roof sheets supported by and riveted to said carlines, each of said carlines comprising a main member of inverted channel section with outstanding base flanges at the lower edges of its side walls and a sectional lower plate-like member secured to said base flanges throughout the

length thereof and extending beyond the side plates, said sectional lower member being wider than said main member and having up-standing side marginal flanges extending above the base flanges of said main carline member.

6. A car roof comprising side plates, hollow carlines connecting said plates and having downturned end portions overhanging portions of said side plates, and roof sheets supported on and riveted to said carlines, each of said carlines comprising a main member and a sectional lower plate-like member secured to said main member throughout the length thereof and extending beyond the side plates.

7. A car roof comprising side plates, hollow carlines connecting said plates and having downturned end portions overhanging portions of said side plates, and roof sheets supported on and riveted to said carlines, each of said carlines comprising a main member and a sectional lower plate-like member secured to said main member throughout the length thereof, said lower member comprising a ridge section, side sections disposed on opposite sides of said ridge section, and end section shaped to conform to the downturned ends of said carline and extending beyond the side plates.

8. A car roof comprising side plates, hollow carlines connecting said plates and having downturned end portions overhanging said side plates, and roof sheets supported on and riveted to said carlines, each of said carlines comprising an upper member of inverted channel section and a lower outwardly and downwardly inclined plate-like member secured to said carline throughout the length thereof, said lower member comprising a plurality of sections arranged with the outer ends of the inner sections overlapping the inner ends of the outer sections, the end sections being secured to the side plates.

9. A car roof comprising side plates, hollow carlines connecting said plates with their ends bent down over said side plates and left open, and roof sheets supported on and riveted to the tops of said carlines, each of said carlines comprising an upper member open at its bottom and a lower closure plate secured to the bottom of said upper member throughout the length thereof and extending over said side plates, said lower member having a series of holes therein that are offset with relation to the rivets that secure the roof sheets to the tops of said carlines.

10. A car roof comprising side plates, hollow carlines connecting said plates with their ends bent down over said side plates and left open, and roof sheets supported on and riveted to the tops of said carlines, each of said carlines comprising an upper member open at its bottom and a lower closure plate secured to the bottom of said upper member through-

out the length thereof, said lower member having a series of holes therein that are offset with relation to the rivets that secure the roof sheets to the tops of said carlines, said closure plate comprising a plurality of sections arranged end to end in overlapped relation.

11. A car roof comprising side plates, inverted channel-shaped carlines connecting said plates and having downturned end portions overlapping said side plates, and roof sheets supported on and riveted to side plates and said carlines, and a lower plate-like member secured to each carline through the length thereof, said lower member comprising a ridge section, duplicate side sections disposed one on each side of said ridge section, and duplicate end sections, said end sections being provided with depending flanges that are secured to the outer faces of the side plates between the latter and the downturned ends of the carlines.

Signed at New Kensington, Pennsylvania,
this 26th day of December, 1930.
